VALVE FLAP FOR MOUTH ORGANS

Hans Bibus, Kusnacht-Zurich, Switzerland

Application September 13, 1947, Serial No. 773,910
In Switzerland September 18, 1946

2 Claims. (Cl. 84—377)

1

In the case of high-quality mouth-organs use is made with a view to preventing the escape of air and to improving the tone, of valve flaps which close the suction reed slots when the user blows and the expulsion reed slots when the user draws in air. These flaps have hitherto almost always been made of sheepskin, which owing to its suppleness and fine hair is a very good sealing medium although only so long as it is dry. As soon as these sheepskin flaps are moistened on one side by the condensation water which almost inevitably collects in mouth-organs, they crinkle and no longer perform their intended function.

If a smooth and non-absorbent material such as rubber or some elastic plastic is used for the flaps, this crinkling effect is avoided, but on the other hand the condensation water, by its surface tension, causes the smooth flaps to adhere to the reed-plate.

The present invention relates to a valve flap which eliminates the disadvantages presented by the known types of valve flaps. The valve flaps for mouth-organs in accordance with the present invention are characterized by the fact that the flaps are so designed that they rest by their edges on the reed-plates. The flap itself may be tapered or concave so as to lie on the edges of the reed slots, or else the valve flap may be convex and taper to an edge with which it rests on the reed-plate. Such hollow or channeled flaps have the further advantage over prior structures that with the same stiffness of the flaps, larger amplitudes of the vibrating reeds can be attained without their striking the flaps.

With valve flaps designed in accordance with the invention the condensation water can cause only negligible adhesion along the edges of contact and materials can therefore be used which are insensitive to water, such for instance as rubber or elastic plastics, which have a smooth surface. The material may be chosen exclusively on the basis of its elasticity and specific weight, without it being necessary to take into consideration the phenomena of adhesion peculiar to the usual design.

In the enclosed drawing Figs. 1 to 9 exemplify a number of typical embodiments of the invention, as follows:

Fig. 1 the reed-block of a mouth-organ;

Figs. 2 and 3 a first embodiment of a valve flap;

Figs. 4 and 5 a second embodiment of a valve flap;

Figs. 6 to 8 various convex embodiments of the valve flap;

Fig. 9 a special type of hollow flap.

In Fig. 1, 1 designates the wooden grid, 2 and 2' the upper and lower reed-plates, 3 and 4 the upper and lower blowing apertures. In the upper reed-plate 2 the suction reeds are designated by 5, the blowing reeds by 6 and the valve flaps covering the blowing reeds 6 by 7.

2

Fig. 2 shows a valve flap 8 of tapered cross-section which is glued to the reed-plate 2 by its end 10 and projects into the reed-slot 6, sealing the said reed-slot 6 along the edge 9.

5 In Fig. 4 a valve flap 11 in the form of a tube segment is shown. This again is glued to the reed-plate 2 by its end 12 and projects into the reed-slot 6. Here again the valve flap rests along the edge of the reed slot 6.

10 Figs. 6-8 show constructional embodiments of valve flaps which do not rest along the reed-slot edges but are supported by their own edges on the reed-plate 2. In Fig. 6 the valve flap 12 rests by its edge 14 on the reed-plate 2. Similarly the 15 valve flap 15 rests along its own edges, i.e. along the edge 16 in Fig. 7, and the same applies to the valve flap 17 in Fig. 8.

In Fig. 9 a hollow flap is illustrated which can be produced as a moulding from rubber, thermoplastic or any other elastic material in various lengths corresponding to the reed-slots. At one end only the flap has a surface 19 underneath with which it is glued at the reed-rivet on the reed-plate. The side-walls 17 and the front 25 wall 18 taper downwards to edges 20, which lie in the same plane as the surface 19, so that the hollow part of the flap lies on the reed-plate along these edges 20 and seals the reed-slot 6 on all sides.

30 All these constructional embodiments have the common feature, mentioned at the outset, that they seal only along the edges, either by the edges of the reed-slots lying against the surface of the valve, or by the valve flap itself being designed 35 in such a way that it rests by its edges on the surface of the reed-plates.

I claim:

1. In a mouth organ, the combination with a 40 reed-plate having a series of reed slots, of means for closing said slots comprising valve flaps of channel cross-section having relatively sharp side edges, the flaps being secured to the reed-plate at one end in such manner that they engage the plate mainly along said sharp edges.

45 2. A mouth organ as set forth in claim 1, wherein in the reed-slots are provided with separate, individually molded flaps of plastic material.

HANS BIBUS.
